York, N. Y., a corporation of New York

Application March 16, 1935, Serial No. 11,429

17 Claims. (Cl. 237—10)

This invention relates to a steam heating system, and more particularly to what is known as a one-pipe system, although equally applicable to certain two-pipe systems or to a system which 5 combines the one and two-pipe principles, and with special reference to the heating of small and medium sized buildings where the steam is supplied to the radiators at relatively low pressures; and one object of the invention is to improve the 10 circulation and distribution of steam to a group of radiators and to so regulate the heat given off thereby as to enhance the comfort and health of the occupants, reduce the water noises, and effect an economy in fuel or steam, while a further 15 object is to provide a simple automatic temperature control whereby to effect with a single thermostat located in a key or chosen position therein a more uniform distribution of the steam and consequent equalization of the heat in all parts of 20 a small building or in a zoned section of a larger building.

A one-pipe heating system may be described as consisting of a source of steam supply, either a boiler or supply main, a damper regulator or a 25 valve for regulating the pressure and consequently the flow of steam, distributing pipes and risers leading from the regulator valve to the radiators, radiator supply shut-off valves, radiator air valves, and drip pipes and a wet return 30 pipe or pipes.

In ordinary everyday practice such systems are installed for the sole reason that they are lower in first cost, and little has been done to improve their operation as compared with the improvements which have been made in two-pipe systems.

So far as I am aware, the only regulation heretofore provided in any actual commercial installation, in the infrequent cases in which regulation 40 has been attempted, has been by intermittently supplying the steam thereto, and even when so regulated these systems are not only inefficient but are also more or less irregular and often noisy in operation.

45 Also, in the more expensive two-pipe systems equipped with the usual on and off thermostatic control there is always a lag in response to the thermostat—sometimes called "fly-wheel" effect—causing short periods of alternate overheat- 50 ing and overcooling, which will be the more pronounced the farther away the radiator is located, and overheating and overcooling effects will also be produced in those remaining in use by the turning off and on of some of the radiators.

I have remedied these long known and long outstanding defects in the one-pipe heating system and have improved the two-pipe system by my present invention, which in its simplest form comprises, essentially, control apparatus (such, 5 for example, as that shown and described in Letters Patent No. 1,935,166 issued to me under date of November 14, 1933, or some modification thereof) adapted to automatically regulate the supply of steam, whether from the boiler of a 10 furnace or from a supply main, so as to shut it off entirely or to effect a flow thereof through the distributing pipe or pipes and to the several radiators of the system under one of two or more accurately defined pressures—for example, one 15 predetermined maximum pressure and a second some predetermined and preferably small fraction thereof—when and as required by temperature conditions within the building or the zone to be heated, and, cooperating therewith, 20 means permitting the escape of air from the main distributing pipe and radiators equipped with at least two air valves—a primary air valve, which is located at or adjacent the inlet end of the radiator, not at its outlet end as heretofore, 25 and which preferably opens to allow the escape of air from the distributing and branch pipes under a light pressure, slightly below that of the steam when supplied at the predetermined low pressure, and closes when reached and heated by the 30 steam, and a secondary air valve, a modification of the primary valve, which may be and preferably is located at or close to the lower corner of the outlet end of the radiator and is operative to allow the escape of the air therefrom only under 35 a pressure approximately that of the steam when supplied at the predetermined maximum pressure, closes when reached and heated by the steam, and on cooling reopens to admit outside air to the radiator.

40 Thus, in my new system, steam is supplied to a group of radiators as required, and under automatic control, by the temperature conditions within the area to be heated to effect a full heating of the radiators, whenever their full heat- 45 ing is called for, in successive steps, or by successive stages, as follows: (1) steam is supplied under low pressure to each radiator of the group with an escape of air through a free flowing thermo float valve on the outer end of the distributing pipe and the primary air valve on the radiator and so fills and heats the pipes and the radiator itself up to this valve; (2) the steam, after heating and closing this valve, and still 50 under low pressure, partially compresses the air 55

within the radiator and so reaches and heats the part of the surface of the radiator so exposed; (3) on the building up of the pressure thereon the steam further compresses the air within the radiator and the secondary air valve, opening under the pressure and allowing the air to escape therefrom, fills and heats the main body of the radiator; and (4) on the closure of this latter valve when reached and heated, the steam, now under high pressure, further compresses such residual air as may remain to thereby expose still more of the surface of the radiator for the effective transference of heat. Then, when temperature conditions within the heated area call for less than full heating, the steam supply is cut off and is kept off for a period sufficient to allow the radiator to cool down and by the partial vacuum created by the condensation of the steam therein to draw in air through the secondary air valve to recharge the system with air, in readiness for a repetition, or partial repetition, of the cycle.

For a full understanding of the invention reference will be made to the accompanying drawings, in which—

Figure 1 is a diagrammatic view of a combination one- and two-pipe heating system, illustrating one practical embodiment of my improvements, as applied to such a system; Fig. 2 is a view, in vertical section and on an enlarged scale, of the air valve here used on the radiators as the primary air valve; and Fig. 3 is a view, similar to Fig. 2, of the upper part of the valve as modified to serve as the secondary air valve.

Referring to the drawing, and assuming that the system is designed to operate under a steam pressure of say eight ounces per square inch for full heating and of one-half ounce for partial heating, 1 indicates the supply pipe or main through which steam is supplied to the system, and 2 is the regulating valve which controls the quantity thus supplied and which is operatively connected with and is actuated by the motor 3, here shown as a vapor-tension motor of standard make. From the low pressure side of the regulating valve the steam is conducted through a distributing pipe 4, provided with an ordinary check-valve 5, to admit air thereto upon the formation of the partial vacuum, to branch pipes 50 or risers 6, 6 and thence through the usual steam shut-off valves 7, 7 to a plurality of radiators 8, 8 and 8^a, 8^a, the radiators 8^a, 8^a being additionally provided with return pipes 9, 9 to a water return main 10 which is provided as usual with an air-vented water seal trap 11. The distributing pipe 4 is also connected at its outer end as usual to the water return main 10 by a drip pipe 12, and at least in the larger installations, with a free flowing thermo float valve 13.

Each of the radiators is equipped on its inlet end with a primary air valve 14 and on its opposite or outlet end with a secondary air valve 15, the primary valve being preferably located as low down on the radiator as practicable and the secondary air valve close to the bottom thereof, especially in the case of the one-pipe radiators 8, 8.

Each primary air valve 14, of the thermo float type, consists of the usual outer casing 16 from the base of which projects a nipple 16^a, by which the valve is connected with a threaded opening in the wall of the radiator. The usual sealed and longitudinally expandable inner chamber 17, containing the volatile substance, is suitably supported at the lower part of the outer casing and

at its upper end carries a valve 18. And the screw plug 19, set into the upper end of the outer casing, and cap 20 together provide a seat for the valve 18, an air passage 21, and an outwardly opening check-valve consisting of the valve chamber 22, ball 23 seating on the enlarged upper end of the passage 21, and air passages 24, 24. The weight of the ball is so proportioned to the area of the opening on which it is seated that it will lift on a light pressure, say one-half ounce, sufficient to force the steam the entire length of the distributing pipe 4 before it starts up the riser pipes 6, 6 to the radiators, thus insuring an even distribution of steam to the radiators whatever the length of the main distributing pipe. In tall buildings however, it will usually be found desirable to omit this ball, leaving the valve a free flowing valve, on the radiators of the top floor with an up feed and of the bottom floor with a down feed system.

The secondary air valves 15 are or may be like the primary valves in all respects except that for the threaded plug 19 and cap 20 of the latter there is substituted a plug 19^a and cap 20^a which provide a passage 21^a with seat for the valve 18, and two check valves—one opening outwardly and the other opening inwardly—consisting of lower valve chamber 22^a, ball 23^a seating on the upper end of the passage 21^a, passage 24^a connecting the top of valve chamber 22^a with the bottom of upper valve chamber 25, ball 26 seating on the upper end of the passage 24^a, by-pass 27 from passage 21^a to upper valve chamber 25, and outlet-inlet passage 28 between passage 24^a and the outer air. This valve functions, when the main valve 18 is withdrawn from its seat, to allow the escape of air through the passage 21^a, lower valve chamber 22^a and passages 24^a and 28, but only when the pressure within the radiator is sufficient—approximately eight ounces, the pressure required for full heating—to raise the ball 23^a from its seat; and, on the shutting off of the steam and the cooling of the radiator, the partial vacuum thus created, lifting the ball 26 from its seat, draws in the outer air through the passages 28 and 24^a, upper valve chamber 25, by-pass 27, and passage 21^a.

The valve actuating motor 3 is supplied with electric current, to heat its operating coil 29, from a suitable source such as the secondary winding 30 of a small transformer, over circuits which include the conductor wires 31, 32, 33, 34, 35, 36, 37, 38 and 39, and which may be, and in the embodiment of the invention here illustrated are, controlled jointly by what may be designated as a dual-controlled thermostat 40 and pressure-responsive device 41, with a secondary control by the time clock 42 and timing device 43, all as presently to be described.

The thermostat 40 has, as shown, three spring contact-fingers 72, 71 and 70, suitably supported and carrying the usual contacts, and attached to the outer face of contact-finger 72 and forming part thereof is the usual bimetallic thermostatic element 72^a so arranged that on cooling this finger bends to the left and on heating bends to the right. The arrangement and adjustment of its parts are such that, with a day-time setting at a mean room temperature of 72°, for example, the contact-fingers will be in the relative position shown, with both sets of contacts open. If the temperature drops say one degree, to 71°, contact-finger 72 will be bent to the left to an extent sufficient to close its contact against the cooperating contact of contact-finger 71, and on a fur-

ther drop of the temperature, say to 70°, the contact-finger 72 will be bent further to the left and through the contacts previously closed will cause contact-finger 71 to bend to the left to close its contact against that of contact-finger 70; and on a rising temperature the contacts will open in the reverse order to that in which they have closed.

The pressure-responsive device 41 is of the usual spring-bellows type commonly employed in steam-heating work, and consists of a chamber which is closed by a spring-bellows (with or without supplemental spring) and which is in direct communication with the steam on the low pressure side of the regulating valve at some convenient point in the distributing system—the upper end of the vertical component of the distributing pipe 4 as here shown. The head of the spring-bellows carries a stem 44 which moves upwardly and downwardly with the movement of the bellows on variations in the pressure of the steam within the distributing pipe and to an extent directly proportional to such steam pressure variations and by its movement controls the contacts of two electrical switches 45 and 46, the parts being so coordinated and adjusted that with a pressure of steam not exceeding the predetermined low pressure of one-half ounce for partial heating the normally closed contacts of both switches will remain closed, but on a rise of pressure slightly above such predetermined low pressure the stem bears down on the movable member of switch 45 and opens its contacts and on a further rise of the pressure to the predetermined maximum of eight ounces for full heating acts through the movable member of switch 45 to press down the movable member and open the contacts of the switch 46, the contacts of these two switches closing in reverse order when the steam pressure falls below such maximum and predetermined low pressures, respectively.

The time clock 42, which is a standard device, comprises two electrical switches 47 and 48 and a clock mechanism so operatively connected therewith that, according to its setting, it will at some evening hour open and hold open during the night the contacts of both switches, and at some early morning hour will first close the contacts of the switch 47 and some ten or fifteen minutes later will close the contacts of the switch 48, the contacts of both switches being then held closed through the day.

The timing device 43 comprises a relatively heavy bimetallic element 49, which is suitably fixed at its lower end and connected thereto to the conductor wire 34, and at its upper end normally bears against a contact 50 to which the conductor wire 33 is attached; and surrounding it and insulated therefrom is a heating coil 51, the ends of which are respectively connected to the conductor wires 36 and 37. The two metallic strips which make up this element are so disposed that when it is heated by current passing through the coil 51 it will flex to the right and its upper end will move away from the contact 50, and its sectional area is such that it will cool and flex to the left slowly so as not to again make contact with contact 50 for say five or six minutes after the circuit through its heating coil has been broken.

The operation of the system in controlling the distribution of steam to and the heat given off from a group of radiators is as follows:

During the night the circuit through the heat-

ing coil of the valve motor is broken at the contacts of both switches of the time clock, the regulating valve is closed so that no steam is supplied to the radiators, and the room temperature is accordingly reduced, say below 70°, and hence both sets of contacts of the thermostat at its daytime setting will be closed. When, therefore, the time clock acts to close the contacts of switch 47, a circuit is established through the heating coil 29 of the motor by wire 31, coil 29, wire 32, 10 contacts of switch 45, wire 33, contact 50, bimetallic element 49, wire 34, contacts of switch 47, wire 35, contacts of contact-fingers 71 and 72, and wire 39 from and back to the transformer winding 30. Thereupon, the motor 3 is 15 operated to lift the valve 2 from its seat and steam flows through and fills first the distributing pipe 4, the air valve 13 permitting the escape of air therefrom, and then the riser pipes 6, 6 and the inlet end of the radiators up to and, 20 due to the partial compression of the air therein, slightly beyond the primary air valves 14, 14. But for the period of ten or fifteen minutes before the time clock closes the contacts of switch 48, the steam will be supplied at approximately 25 the predetermined primary or low pressure of one-half to one ounce, since whenever it rises slightly above such pressure the pressure-responsive device 41 will be actuated to press its stem down upon and open the contacts of switch 45, 30 breaking thereat the circuit through the heating coil of the motor which thereupon cools and on cooling permits the regulating valve to close slightly until on the drop of pressure thereby effected the contacts of this switch are again closed, to reestablish the actuating circuit of the motor and effect a lift of the valve sufficient to restore the pressure. The pressure-responsive device thus serves, by alternately opening and closing the contacts of switch 45 on slight variations of the pressure either above or below that selected for partial heating, to hold the motor 35 and valve in the required position within the very close limits defined by such pressure variations.

Moreover, the partial heating of the radiators 45 thus effected will be continued during the ten or fifteen minutes which must elapse before the time clock closes the contacts of switch 48, unless it is sufficient to raise the room temperature above say 71° to thereby break the motor circuit at the thermostat; and this partial heating will be uniform for all radiators in the group, regardless of the size of each, since the volume of the air remaining bound within the radiator on the closing of its primary air valve when 55 reached and heated by the steam, with the slight compression thereof which takes place after the closure of the valve, will in all cases be directly proportional to the total heat transfer capacity of the radiator. For illustration, a small radiator of say 30 square feet rating, having 7200 B. t. u. total heat transfer capacity, will have a volumetric capacity of 0.75 cubic foot, and one of double or 60 square feet rating and 14,400 B. t. u. total heat transfer capacity will have 60 double, or 1.5 cubic feet, capacity; and when their primary air valves are closed, the exposure to the steam of the heat transfer surface of each, upon the partial compression of the bound air therein under the low pressure, will be in the 65 same proportion so that if the small radiator is thereby 20 per cent. heated the larger radiator will likewise be 20 per cent. heated.

On the closure of the contacts of clock switch 48 and assuming that the period of partial heat- 75

ing has not so raised the room temperature as to effect an opening of contact-fingers 70 and 71, a new circuit will thereby be established through the heating coil of the motor, parallel to that above described, from wire 32, closed contacts of switch 46, wire 36, coil 51, wire 37, contacts of switch 48, wire 38, contact-fingers 70, 71 and 72 and wire 39. The motor, continuing to operate, will further lift the regulating valve and as the valve opens the pressure on the steam supplied therethrough to the radiators will be built up, opening the motor circuit at the contacts of switch 46 and further compressing the air bound within the radiators and heating up more of their surface, until it is sufficient to open the secondary air valves 15, 15, whereupon with the escape of air therefrom the steam substantially fills and heats practically the entire heat transfer surface of the radiators. 20 And, as before, the pressure-responsive device 41 serves to hold the motor and valve closely to the position required to supply steam to the radiators at the predetermined maximum pressure for full heat, so long as the contacts of 25 the contact-fingers 70 and 71 remain closed, by alternately opening and closing the motor circuit on variations of pressure slightly above and slightly below such maximum, preventing an over-supply of steam to the radiators. In case, 30 however, the conditions are such that the partial heating of the radiators effects a rise in the room temperature slightly above 70° before the time clock closes the contact switch 48, the closing of this switch will be without effect since 35 the new circuit through the coil of the motor closed thereat will be broken at the contacts of the thermostat. Accordingly, the circuit controlled by switch 45 of the pressure-responsive device will continue to so operate the motor as 40 to hold the reducing valve in its position for partial heating. But if at any time this partial heating of the radiators so raises the room temperature, above say 71°, that the thermostat opens the contact between its contact-fingers 71 and 45 72, the motor circuit will be broken and the regulating valve will drop and remain closed until the room temperature falls and the thermostat again closes contact between its contact-fingers 71 and 72, whereupon the motor will be started 50 to again lift the valve to restore the system to a condition of partial heating.

Assuming, however, that the temperature conditions are such that a full heating of the radiators is required to raise the room temperature to 55 say 71°, on a slight further rise the thermostat will open the contacts of its contact-fingers 71 and 72, breaking thereat the circuit through the heating coil of the motor, and so allows the motor to cool and the regulating valve to close. But 60 during every period of full heating the motor is controlled by the circuit which includes the contacts of switch 46 of the pressure-responsive device and the coil 51 of the timing device 43, and this coil so heats the bimetallic element 49 that 65 it bends to the right out of contact with the contact 50, thereby breaking at this point the operating circuit of the motor for partial heating which includes the contacts of switch 45 of the pressure-responsive device. Hence, on the breaking 70 of the motor circuit at the thermostat after a period of full heating, the motor cannot again be started, to lift the regulating valve, until after the lapse of the period required by the bimetallic element 49 to so cool as to bend back to the left 75 and again make contact with contact 50, with the

result that during this period of delay the radiators will have had time to so cool down and condense the steam therein as to produce a vacuum sufficient to raise the ball in the upper valve chamber of their secondary air valves and draw in 5 outside air to restore them to condition for a resumption of partial heating, and later of full heating for and as required and under control of the thermostat on the closure at the contact 50 of the operating circuit of the motor through the 10 contact switch 45.

The operative principle of the system, in whatever form it may be embodied for practical use, is that the steam supplied to heat the radiators is admitted to the interior thereof in stages, first 15 with moderate flow and under low pressure to the inlet end only of the radiators, and finally, if required by temperature conditions, at full flow and under relatively high pressure to practically the 20 entire interior of the radiators.

By thus heating the pipes and radiators gradually, or by stages, I reduce to a very considerable extent the heavy starting demand for steam, and consequent abnormal amount of water condensate, characteristic of the ordinary one-pipe heating system, with the result that the pipe capacity is not overtaxed and the condensate will flow smoothly back therethrough in counter-current to the supply steam; and further, because of the resultant reduction in the accumulated condensate, I am able, without interference therefrom, to connect the secondary air valves to the radiators close to the bottom of their far ends, thereby reducing to a minimum the amount of the residual air which will be entrapped and "bound" 35 therein. In consequence, I am able to promptly effect, without lag or "fly-wheel" effect, a substantially uniform distribution of the steam to a group of radiators, regardless both of their location and of variations from time to time of the 40 number thereof in use, whether at a low pressure for partial heating or at a higher pressure for full heating as selectively determined by the thermostat according to the prevailing weather conditions, and to accomplish all this with the elimination of most if not all of the water noises and a 45 material saving both in first and in operative cost.

While I have shown and described my improved system as controlled by a regulating valve operated by a vapor-tension motor, it is to be understood that an electro-magnetic motor, gravity motor, air, oil, or water motor, or motor power of any suitable type, may be substituted therefor; and in case the regulating valve is of the type actuated by a screw-spindle the motor to be used 55 therewith will of course be one adapted to effect a rotary instead of a reciprocating movement of the spindle. The desired regulation can also be effected, as hereinabove indicated, by operatively connecting the motor to the dampers of the 60 furnace of a steam boiler as in my earlier patent.

It is also to be understood that, while the motor has been shown and described as jointly controlled in its operation by a thermostat and a pressure-responsive device, equivalent devices 65 may be substituted for either or both thereof, or either or both may be omitted and the motor controlled, if desired and within the scope of the appended claims, by any other suitable means—for example, a manually operated remote control 70 switch instead of the thermostat, especially in a large building where an engineer is employed. Moreover, the temperatures and pressures mentioned, in degrees Fahrenheit and in gauge pressures, respectively, are merely illustrative and 75

may be varied as desired—higher pressures being required in installation for large buildings and occasionally and under special conditions even in small buildings—and the pressure-responsive device, when used, need not be associated with the distributing pipe as shown but may be operatively connected with the distributing system at any suitable point, as on the low pressure side of the valve itself or elsewhere.

10 10 What I claim as new, and desire to secure by Letters Patent, is—

15 1. An automatic air valve for a steam radiator comprising a main float and thermostatically actuated valve which is normally open and is closed by heat and/or water, and, mounted upon the outer end of the fixed valve member a cap providing passages connecting the outlet of the valve with the air outside and controlled respectively by a one-way ball valve opening to permit the outward flow of air under a relatively high differential pressure and a one-way ball valve opening to permit the inward flow of air under a light differential pressure.

20 2. In a heating system of the type described the combination, with a source of steam supply and a plurality of radiators connected by piping therewith, of means operative to selectively provide a substantially constant supply of steam from the supply source to the radiators at one of two predetermined pressures, either a low pressure for a partial heating or a higher pressure for the full heating of the radiators, and means operative on the starting up of the heating system after a shutting down thereof to maintain the supply of steam to the radiators at the lower pressure for a predetermined time interval before it can be raised to the higher pressure.

25 3. In a heating system of the type described the combination, with a source of steam supply and a plurality of radiators connected by piping therewith, of a motor actuated valve controlling the admission of steam from the supply source to the radiators, and control means for the valve motor operative to effect a shifting of the valve 30 adapted to maintain substantially constant the supply of steam to the radiators at one of two selectively determined pressures, either a low pressure for a partial heating or at a higher pressure for the full heating of the radiators, and including a timing device operative when the heating system is started up after a shutting down thereof to maintain the supply of the steam to the radiators at the lower pressure for a predetermined time interval before it can be raised 35 to the higher pressure.

40 4. In a heating system of the type described the combination, with a source of steam supply and a plurality of radiators connected by piping therewith, of means operative to selectively provide a substantially constant supply of steam from the supply source to the radiators at one of two predetermined pressures, either a low pressure for a partial heating or a higher pressure for the full heating of the radiators, including timing means operative to interpose a predetermined time interval after the end of a period at which the steam has been supplied to the radiators at the higher pressure before the steam can again be supplied thereto.

45 5. In a heating system of the type described the combination, with a source of steam supply and a plurality of radiators connected by piping therewith, of a valve controlling the flow of the steam from the supply source to the radiators, a 50 motor controlling the valve, and control means

for the motor operative to effect a shifting of the valve adapted to maintain the supply of steam to the radiators substantially constant at one of two selectively determined pressures, either a low pressure for a partial heating or a higher pressure for the full heating of the radiators, said control means including a timing device operative after the end of a period at which the steam has been supplied to the radiators at the higher pressure to interpose a predetermined time interval before the steam can again be supplied thereto.

55 6. In a heating system of the type described the combination, with a source of steam supply and a plurality of radiators connected by piping therewith, of means operative to provide a supply of the steam to the radiators substantially constant at one of two selectively determined pressures, either a low pressure for a partial or a higher pressure for the full heating of the radiators, timing means operative on the starting up of the system after a shutting down thereof to interpose a predetermined time interval during which the steam will be supplied to the radiators at the lower pressure before it can be supplied thereto at the higher pressure, and a second timing means operative after the end of a period at which the steam has been supplied to the radiators at the higher temperature to interpose a predetermined time interval before the steam can again be supplied to the radiators.

60 7. In a heating system of the type described the combination, with a source of supply and a plurality of radiators connected by piping therewith, of a valve controlling the flow of the steam from the supply source to the radiators, a motor controlling the valve, and control means for the motor including a thermostat responsive to temperature in the area heated by the radiators and a pressure device responsive to pressure on the low pressure side of the valve operative to maintain a supply of the steam to the radiators substantially constant at either one of two given pressures as selectively determined by the temperature responsive device, and two timing 65 means one operative on the starting up of the system after a shutting down thereof to maintain the supply of steam to the radiators at the lower pressure for a predetermined time interval before it can be raised to the higher pressure and the second operative after the end of a period at which the steam has been supplied to the radiators at the higher pressure to interpose a predetermined time interval before the steam can again be supplied to the radiators.

70 8. In a heating system of the type described the combination, with a source of steam supply and a plurality of radiators connected by piping therewith, of automatic means for securing either a substantially equal partial heating or a substantially equal full heating of all the radiators of the group as selectively determined by a device responsive to variations in the room temperature, said means including means for supplying the steam at a relatively low pressure to first expel the air from and fill the main distributing pipes and thereafter to expel the air from the branch pipes to and the inlet portions only of the radiators and for supplying the steam at a higher pressure to expel the air from and substantially fill the entire bodies of the radiators, and means operative when after a period of full heating of the radiators a partial heating only is required to interpose a time interval between the cutting off and again cutting on of the supply.

of steam sufficient to allow the radiators to cool and become recharged with air.

9. In a one-pipe heating system the combination, with a source of steam supply and a plurality 5 of radiators connected by piping therewith, of a vapor-tension motor controlling the amount of steam supplied to the radiators, electric circuits for said motor, control means for said electric circuits including a thermostat responsive to 10 changes in room temperature and a pressure device responsive to variations in the pressure of steam in the piping to the radiators operative to provide a substantially constant supply of steam to the radiators at one of two predetermined pressures as selectively determined by the thermostat, 15 and means including thermo air valves associated one with the main line of piping and one with each end of the several radiators operative to allow the steam when supplied at the lower pressure first to expel the air from and fill the main 20 line of piping and thereafter to expel the air from and fill the branch lines of piping to and the inlet ends only of the radiators and to allow the steam when supplied at the higher pressure to 25 expel the air from and fill substantially the entire bodies of the radiators.

10. In a one-pipe heating system the combination, with a source of steam supply and a plurality of radiators connected by piping therewith, of 30 means for providing a substantially constant supply of steam from the supply source to the radiators at one of two selectively determined pressures, a thermo air valve associated with the inlet end of each radiator adapted to open to allow the 35 escape of air therethrough only under a pressure approaching the lower pressure at which the steam is supplied to the radiators and to prevent any intake of air therethrough, and a thermo air valve associated with the outer end of each 40 radiator adapted to open to allow the escape of air therethrough only under a pressure approaching the higher pressure at which the steam is supplied to the radiators and on the shutting off of the steam and the cooling of the radiator 45 to permit the ingress of air therethrough.

11. In a one-pipe heating system the combination, with a source of steam supply and a plurality of radiators connected by piping therewith, of 50 means for providing a substantially constant supply of steam from the supply source to the radiators at one of two selectively determined pressures, a thermo air valve associated with the inlet end of each radiator adapted to open to allow the escape of air therethrough only under 55 a pressure approaching the lower pressure at which the steam is supplied to the radiators and to prevent any intake of air therethrough, a thermo air valve associated with the outer end of each radiator adapted to open to allow the 60 escape of air through a one-way ball valve opening outwardly only under a pressure approaching the higher pressure at which the steam is supplied to the radiators and on the shutting off of the steam and the cooling of the radiator to permit 65 the ingress of air through a second one-way ball valve opening inwardly, and means operative when the steam is turned off after a period during which it has been supplied to the radiators at the higher pressure to interpose a time interval 70 before the steam is again supplied thereto sufficient to allow the radiators to cool and become recharged with air.

12. In a one-pipe heating system the combination, with a source of steam supply and a plurality 75 of radiators connected by piping therewith, of

means for providing a substantially constant supply of steam from the supply source to the radiators at one of two pressures as selectively determined by the room temperature, a free venting thermo air valve associated with the main piping 5 to the radiators operative to allow the steam to expel the air therefrom and to fill the same at a pressure materially below the lower of the two pressures at which the steam may be supplied to the radiators, a loaded thermo air valve associated with the inlet end of each radiator operative to allow the escape of air therethrough at a pressure approaching the lower of the two pressures at which the steam may be supplied to the radiators, and a loaded thermo air valve associated with the outer end of each radiator operative to allow the escape of air therethrough only at a pressure approaching the higher of the two pressures at which the steam may be supplied to the radiators, the air valve associated with the outer 20 end of each radiator being adapted to permit the ingress of air through a one-way ball valve opening inwardly on the cooling of such end of the radiator.

13. In a one-pipe heating system the combination, with a source of steam supply and a plurality of radiators connected by piping therewith, of means controlled by devices responsive respectively to temperature and to pressure for maintaining the steam supplied to the radiators substantially constant at either one of two given pressures as selectively determined by the temperature responsive device, means permitting the escape of air from the inlet ends of the radiators under the lower and from the outer ends of the radiators under the higher of the two said steam pressures, and means for recharging the radiators with air when after a supply of steam thereto at the higher pressures a supply at the lower pressure only is required.

14. In a one-pipe heating system the combination, with a source of steam supply and a plurality of radiators connected by piping therewith, of a motor controlling the amount of steam supplied to the radiators, control means for said motor including a device responsive to variations in the room temperature and a device responsive to variations in the pressure of the steam in the piping to the radiators and adapted to selectively maintain the same substantially constant at a 50 given maximum or at a given fraction of such maximum as selectively determined by the temperature responsive device, means associated with the respective radiators permitting the escape of air at their inlet ends only under the fractional 55 and at their outer ends under a full pressure of steam, and means for delaying the supply of steam to the radiators at a full pressure for a predetermined period after a supply thereof at the fractional pressure on starting the operation 60 of the system.

15. In a one-pipe heating system the combination, with a source of steam supply and a plurality of radiators connected by piping therewith, of a motor controlling the amount of steam supplied to the radiators, control means for said motor including a device responsive to variations in the room temperature and a device responsive to variations in the pressure of the steam in the piping to the radiators and adapted to maintain 70 the same substantially constant either at a given maximum or at a given fraction of such maximum as selectively determined by the temperature-responsive device, means associated with the respective radiators permitting the escape of air 75

5 at their inlet ends only under the fractional and at their outlet ends under a full pressure of steam, and means for recharging the radiators with air before steam can again be supplied to the radiators at the fractional pressure after having been supplied thereto at a full pressure.

16. In a one-pipe heating system, the combination, with a source of steam supply and a plurality of radiators connected by piping therewith, of a 10 vapor-tension motor controlling the amount of steam supplied to the radiators, electric circuits for said motor, and control means for said electric circuits including a thermostat responsive at 15 each temperature setting to at least three different degrees of room temperature and a pressure device responsive to variations in the pressure of steam in the piping to the radiators adapted to maintain the pressure of steam to the radiators substantially constant at either a predetermined 20 maximum or at a predetermined fraction thereof as selectively determined by the thermostat, and air valves respectively connected with the inlet and outer 25 ends of the several radiators, the valve at the inlet end of each radiator having a main valve normally open and closed by heat and operatively associated with the outlet end thereof a one-way subsidiary check valve opening outwardly on the application of a light pressure through the main valve, and the valve at the 30 outer end of the radiator having a main valve normally open and closed by heat and operatively associated with the outlet end thereof two one-

way subsidiary check valves one opening outwardly under a pressure through the main valve approximating the full pressure of steam and the other opening inwardly under a light pressure through the main valve.

17. In a one-pipe heating system, the combination, with a source of steam supply and a plurality of radiators connected by piping therewith, of automatic means including a motor for supplying the steam to the radiators at either a predetermined maximum pressure or a predetermined fraction of such maximum pressure as selectively determined by a device responsive to variations in the room temperature, air valves respectively connected with the inlet and outer 15 ends of the several radiators, the valve at the inlet end having a main valve normally open and closed by heat and a one-way subsidiary check valve opening outwardly under a light pressure through the main valve and the valve associated 20 with the outer end having a main valve normally open and closed by heat and two one-way subsidiary check valves one opening outwardly under a pressure through the main valve approximating the maximum pressure of the steam and the other 25 opening inwardly under a relatively light pressure through the main valve, and supplemental control means for the motor adapted to delay the supply of heat to the radiators at the fractional pressure after a supply of steam thereto at the 30 maximum pressure.
